UNITED STATES PATENT OFFICE.

JOHN E. GROSS, OF WALLA WALLA, WASHINGTON.

TRACTION-BELT.

1,305,280.

Specification of Letters Patent. Patented June 3, 1919.

Application filed July 17, 1918. Serial No. 245,297.

To all whom it may concern:

Be it known that I, JOHN E. GROSS, a citizen of the United States, residing at Walla Walla, in the county of Walla Walla and State of Washington, have invented certain new and useful Improvements in Traction-Belts, of which the following is a specification.

This invention relates to tractors and other motor vehicles of the self-laying track or "caterpillar" type, and more particularly to the track by which propulsion is effected.

The object of the invention is to provide a traction unit of the kind stated which is light, strong and durable, and with this object in view, the invention consists in a novel combination and arrangement of parts to be hereinafter described and claimed.

In order that the invention may be better understood, reference is had to the accompanying drawings forming a part of this specification, and in said drawings,

Figure 1 is an elevation of the traction unit;

Fig. 2 is a plan view of a fragment of the belt;

Fig. 3 is a cross section on the line 3—3 of Fig. 2;

Fig. 4 is a cross section on the line 4—4 of Fig. 1;

Fig. 5 is an elevation of a fragment of a modified form of belt;

Fig. 6 is a plan view thereof;

Fig. 7 is a cross section on the line 7—7 of Fig. 6;

Fig. 8 is a cross section of another modification;

Fig. 9 is an elevation showing another form of traction unit;

Fig. 10 is a cross section on the line 10—10 of Fig. 9, and

Fig. 11 is a plan view of a fragment of the belt shown in Fig. 9.

Referring specifically to the drawings, the traction unit is a flat endless belt formed of a single wire cable 10 which is helically wound, with the convolutions closely together and laid side by side, the length of the cable being such as to obtain of belt of the desired width. The cable is held in this belt form by top and bottom clamping plates 11 and 12, respectively. These plates are arranged in pairs, said pairs being uniformly spaced. The top plate 11 is bent down at both ends as shown at 13 to produce a bottom channel in which the cable 10

seats, and the bottom plate 12 seats over this channel. By means of bolts 14 the plates 11 and 12 are fastened together to clamp the cable therebetween the bolts being forced 60 between the convolutions of the cable.

To the under side of each bottom plate 12 is bolted or otherwise secured a tooth 15, the bolts 16 also passing between the convolutions of the cable 10, and through the top 65 plate 11.

By the structure hereinbefore described a very light cable 10 may be employed, and the plates 11 and 12 give great rigidity to the teeth 15. 70

The belt 10 passes over two supporting wheels one of which may be the driver. Each of these wheels is composed of two laterally spaced disks 17 having alined hubs 18. The peripheries of the disks have spaced indentations 19 conforming in width and spacing to the width and spacing of the bars 12. The cable belt 10 is trained over the wheel, with the bars 12 seating in the indentations where the belt passes over the 80 wheel. The peripheries of the disks are outwardly flanged as shown at 20 to obtain indentations 19 of sufficient width.

The two disks 17 are rigidly connected in laterally spaced relation by cross bolts 21, 85 on which are spacing sleeves 21^a, and the latter in turn carry anti-friction rollers 22.

The teeth 15 are positioned at the middle of the belt 10 and the rollers 22 are so spaced that when the belt is properly trained over the disks 17, the teeth are positioned between the disks so as to engage the rollers. The motion of the driver is therefore transmitted to the belt in the same manner as a sprocket-and-chain gearing. As the bars 90 12 seat in the indentations 19 much strain is taken off the teeth 15.

The drive and supporting wheels are carried on shafts 23 and 24, respectively, supported in bearings 25 on a frame 26. One 100 of the bearings is provided with a tightener 27. The lower run of the belt 10 travels over idler wheels 28 having indentations for the plates 12.

The cross plates 11 form the tread of the 105 belt 10.

Figs. 5 to 7 show a tread composed of cross plates 29 set closely together to overlap, one edge of each plate being slightly offset upwardly as shown at 30 to overlap 110 the adjacent edge of the next plate. These plates have bent down ends 31 to confine the

cable 32. It will be noted that the cable is in two sections, the same being located on opposite sides of the teeth 33. The cable sections are clamped to the plates 29 by bottom plates 34, and the teeth 33 are bolted to the bottom of the tread plates 29 between the two cable sections.

Fig. 8 shows a single cable section 35 in conjunction with tread plates 36 similar to 10 those hereinbefore described. The bottom plates are dispensed with and the cable is clamped between the teeth 37 and the tread plates, the base of each tooth having a clip 38 to hold the cable. The clips 38 may be 15 integral with or separate from the teeth 37.

Figs. 9 to 11 show another modification. Here the cable 39 is clamped between top and bottom plates 40 and 41, respectively, as in the first described structure. Each 20 bottom plate 41 carries a plate 42 having outward turned ends 43. This plate 42 has the same function as the teeth 15. The drive and supporting wheels 44 have indentations 45 in their peripheries to seat the plates 42, and 25 the width of the wheels is such that the ends 43 of the plates come alongside the same, thereby preventing the belt from slipping off sidewise.

The advantage of a belt composed of an 30 endless cable arranged in the manner described is that a light cable may be employed, strength being obtained through the many convolutions arranged side by side rather than by a large cable. The necessary 35 rigidity of the teeth is obtained by the cross plates. The stretch is equal and no individual adjustment of the cables is necessary, all necessary adjustment being effected by the tightener 27. As a small cable has

greater flexibility than a large one, there is 40 less appreciable wear to the cable in the continuous bending incident to passing around the curves of the drive and supporting wheels, and the greater flexibility of the belt enables the tractor to negotiate softer 45 ground than heretofore, and with less traction effort.

I claim:

1. A traction belt composed of a flexible cable helically wound with the convolutions 50 laid side by side, and top and bottom cross members between which the cable is clamped laid in the manner stated.

2. A traction belt composed of a plurality of strands of flexible cable laid side by side, 55 top and bottom cross members between which said strands are clamped, and an outstanding drive tooth on the bottom cross member, in combination with a driving wheel comprising a pair of laterally spaced 60 disks, and cross members connecting said disks, the peripheries of the disks having indentations to seat the aforesaid bottom cross members of the belt and the teeth engaging the cross members between the disks. 65

3. A traction belt composed of a series of top and bottom cross members flexibly connected, and an outstanding drive tooth on the bottom cross member, in combination with a driving wheel comprising a pair of 70 laterally spaced disks, and cross members connecting said disks, the peripheries of the disks having indentations to seat the aforesaid bottom cross members of the belt and the teeth engaging the cross members between the disks. 75

In testimony whereof I affix my signature.
JOHN E. GROSS.
